STOKER

William V. Sauter, Philadelphia, Pa., assignor to
American Engineering Company, Philadelphia,
Pa., a corporation of Pennsylvania

Application May 28, 1937, Serial No. 145,211

14 Claims. (Cl. 122—4)

This invention relates to furnace stokers, and more particularly to stokers of the multiple retort underfeed type.

One object of the present invention is to provide an improved fluid cooled system for stokers of the stated character which functions to protect the grates thereof against molten ash and clinker formations.

Another and more specific object is to provide one or more fluid conducting tubes in cooling relation with each of the tuyère rows and portions of the front wall of the ash pocket of the stoker, and one or more tubes above each of the retorts, thereby forming a slag screen across the stoker which acts to chill the molten ash before coming in contact with the grates thereof. The tubes overlying the retorts extend rearwardly and may terminate in the lower header of the bridge wall. These extensions lie in the hot zone at the top of the ash pocket and thereby prevent the fusion of the ash into large clinker masses.

Other and further objects will become apparent as the description of the invention progresses.

Of the drawings:

Fig. 1 is a longitudinal sectional view taken through one of the retorts of a stoker showing the preferred type of fluid cooling system applied to a stoker of the crusher pit type.

Fig. 2 is a plan view partly in section taken substantially along line 2—2 of Fig. 1.

Fig. 3 is a sectional, elevational view taken substantially along line 3—3 of Fig. 1.

Fig. 4 is a longitudinal sectional view taken through one of the retorts of a stoker showing the fluid cooling system applied to a stoker of the dump plate type.

Fig. 5 is a sectional elevational view taken substantially along line 5—5 of Fig. 4.

Fig. 6 is a longitudinal, sectional view taken through the lower end of a stoker showing an alternative arrangement of tubes of the fluid cooling section, and

Fig. 7 is a sectional view taken substantially along line 7—7 of Fig. 6.

Referring first to Figs. 1 to 3 of the drawings, the numeral 1 designates generally a furnace equipped in the present instance with a multiple retort, underfeed stoker 2. Stoker 2 consists of a series of alternately disposed retorts 3 and tuyère rows 4, each retort having provided in the bottom thereof a series of alternately disposed pushers 5 and dead plates 6. Fuel from hoppers 7 is fed to the retorts 3 by rams 8 driven by any suitable power mechanism 9. The pushers 5 are also driven by the power mechanism 9

through a link and lever mechanism indicated generally at 10. An extended dead or coal plate 11 is provided at the lower end of each retort, the rearwardly disposed ends of which being curved downwardly, as shown at 12, forming an overfeed section. The rearwardly disposed end of stoker 2 terminates in a transverse ash pocket 13, having a pair of crusher rolls 14 provided at the bottom thereof. Crusher rolls 14 are supported in any suitable manner on structural supporting members 15.

Each tuyère row 4, as shown in Figs. 1 and 2, has mounted thereon a pair of fluid conducting tubes 16. These tubes extend upwardly and form a portion of the exposed surface of the front wall 17 of the furnace 1. The lower ends of these tubes are bent downwardly and forwardly, as shown at 18, and form a portion of the front wall 19 of ash pocket 13 and terminate in a transverse header 20 mounted in any suitable manner near the lower end of the ash pocket. The upper ends of tubes 16 terminate in one of the steam drums of a boiler (not shown).

Mounted above each retort 3 and extending longitudinally thereof is a tube 21. The upper ends of these tubes extend vertically in abutting relation with front walls 17, and also terminate in one of the steam drums of the boiler. The lower ends of tubes 21 extend across the top of the ash pocket 13, and are bent downwardly, as shown at 21', thereby forming a portion of the rear or bridge wall 22 of the furnace. The tubes 21 are then bent at their lower ends, as shown at 23, and extend rearwardly and terminate in a transverse header 24, which receives the usual tubes 25 provided in the rear wall.

Pivotedly mounted in brackets 26 and 27 are a series of crusher plates 28 and 29 respectively, which cooperate with rolls 14 to crush and feed the ash into an ash pit 30 disposed therebelow. Air is supplied to the tuyère rows of the stoker from a plenum chamber 31, which in in turn receives its air from any suitable fan or blower mechanism (not shown) through a communicating passage 32. Draft air is supplied to the lower end of the stoker from a second chamber 33 disposed therebeneath, which communicates with plenum chamber 31 through a communicating passage 34 having an adjustable damper 35 provided therein.

Headers 20 and 24 are connected to the boiler by downcomer connections 36 and 37 respectively. As shown in Fig. 1, the tubes 21 make a smaller angle with a horizontal plane than tubes 16, so that a space 38 is provided between these tubes 38.

and the upper surface of coal plates 11. By this arrangement the fuel fed by the lowermost pushers 5 may pass through these passages, as well as at the sides thereof, and thus packing of the fuel is prevented. By the arrangement of tubes 16 and 21 just described, it will be observed that a fluid cooled slag screen is provided across the entire width of the stoker which functions to chill the molten ash flowing toward the fuel supporting structure thereof before it comes in contact therewith. Damage to the stoker is thus prevented. It will also be observed that the tubes 21 extend over the top of the ash pocket, and thereby chill the ash contained therein to prevent the same from fusing into large clinker masses. The ash contained in pocket 13 may then be fed at a predetermined rate and the danger of clogging due to large clinker formations is prevented. The lower ends of the tubes 21 also form a portion of the lower rear wall 22, and lie in substantially parallel relation with the tubes 25 of the rear wall proper. By this arrangement the portion of the rear wall of the ash pocket 13, which is subjected to the greatest heat, is effectively cooled. The portions of tubes 25 extending above tubes 21 in the rear wall are bent slightly, as shown at 46, so that the upper extremities thereof are substantially equally spaced across the width of the rear wall 22.

Figs. 4 and 5 show a similar arrangement of tubes in connection with an underfeed stoker 42 of the dump plate type. This stoker also comprises a series of alternately disposed retorts 43 and tuyère rows 44. Each tuyère row also has provided in cooling relation therewith tubes 45 which extend upwardly forming a portion of the exposed surface of the front wall 46 of the furnace. These tubes also extend downwardly in cooling relation with the overfeed section 47 and terminate at their lower ends in a transversely disposed header 48. In this construction also a tube 49 extends longitudinally of and in spaced relation with the bottom of each retort 43. The lower ends of tubes 49 extend across the top of an ash pocket 50 and then are bent downwardly, as shown at 51, and terminate at the lower ends thereof in a transverse header 52 at points between certain of the tubes 53 of the rear wall 54 of the furnace. The partially consumed fuel and refuse is fed from the stoker 42 to a series of dump plates 55 provided at the rear of the stoker. These dump plates are mounted on a square shaft 56. The ends of shaft 56 are round and extend through suitable bearings 57 provided in the side walls 58 of the furnace. A hand lever 59 secured to one end of shaft 56 is provided to actuate the dump plates downwardly from time to time to discharge the ashes from pocket 50 into an ash pit 60 disposed therebeneath.

In this construction, like that shown in Figs. 1 to 3, the tubes 45 and 49 form a fluid cooled screen across the stoker, and function to chill any molten ash flowing toward the fuel supporting structure before coming in contact therewith. The rearwardly disposed ends of tubes 49 overlying the top of ash pocket 50 also function to prevent the ash from fusing into large clinkers and thereby facilitate the discharge thereof into ash pit 60.

Figs. 6 and 7 show a still further modification of the present invention. In this construction the tubes 65 overlying the retorts 66 of the stoker 67 are arranged in substantially the same plane as the tubes 68 overlying the tuyère rows 69. The lower ends of tubes 65 also extend over the top of

the ash pocket 70, and function to chill the ash contained therein and thereby prevent the fusion of the ash into large clinker masses. Referring more particularly to Fig. 7, it will be observed that each of the tubes 65 has welded or otherwise secured to the lower side thereof, a longitudinally extending element 71. These elements provide rigidity to the tubes 65, and also act as deflectors for the fuel fed by the pushers 72 mounted in the bottoms of the retorts 66. It will also be noted that the tubes 65 are mounted in cooling relation with the rearwardly disposed ends of dead plates 73 and thus serve the function of both chilling the molten ash flowing toward the same, and also acting as a direct cooling medium for these plates.

From the foregoing description it is seen that effective fluid cooling systems have been provided which form in effect slag screens across the entire width of the stoker. The tubes are substantially equally spaced across the width of the stoker in each instance, and thereby produce a uniform condition over the entire grate area thereof. By this arrangement of tubes any molten ash flowing toward the grate is chilled before coming in contact therewith, and as a result damage to the grates or to the feeding mechanisms for the fuel is prevented. The portions of the tubes extending over the ash pocket also chill the ash contained therein, and thereby prevents the fusing of the same into large clinker masses. By providing tubes over the retorts of the stoker, as shown and described herein, it is seen that the fuel fed by the rams and pushers is deflected toward the adjacent tuyère rows. This tends to produce a uniform fuel bed and insures greater efficiencies in operation.

While the embodiments herein shown and described are admirably adapted to fulfill the objects primarily stated, it is to be understood that it is not intended to limit the invention to these embodiments since it may be embodied in other forms, all coming within the scope of the claims which follow.

What is claimed is:

1. A stoker having a fuel supporting portion, an ash pocket disposed at one end of said stoker, and a series of fluid conducting members extending longitudinally through the fuel bed and overlying said fuel supporting portion, some of said members extending across the top of said ash pocket.

2. In a furnace having front and rear walls, the combination of a stoker, said stoker extending rearwardly from said front wall and lying in spaced relation with said rear wall, an ash pocket, and a series of fluid conducting members extending longitudinally of, and through the fuel bed supported by, said stoker, some of said members extending across said ash pocket and being so formed as to constitute a portion of said rear wall.

3. In a furnace, having front and rear wall, the combination of an inclined grate stoker extending rearwardly from said front wall, an ash pocket disposed between said stoker and rear wall, a series of fluid conducting members disposed longitudinally of, and through the fuel bed supported by, said stoker, some of said members extending across said ash pocket and being formed to lie in abutting relation with said rear wall, and means for circulating a cooling medium through said members.

4. In a furnace having front and rear walls, the combination of an inclined grate stoker ex-

tending rearwardly from said front wall, said stoker comprising alternately disposed retorts and tuyère rows, an ash pocket disposed between said stoker and rear wall, a series of fluid conducting tubes extending longitudinally of said stoker and overlying said retorts and tuyère rows, some of said tubes extending rearwardly across the top of said ash pocket.

5. In a furnace having front and rear walls, the combination of an inclined grate stoker extending rearwardly from said front wall, said stoker comprising alternately disposed retorts and tuyère rows, an ash pocket disposed between said stoker and rear wall, a series of fluid conducting tubes extending longitudinally of said stoker and lying adjacent said retorts and tuyère rows, the tubes lying adjacent said retorts extending rearwardly across the top of said ash pocket and being formed to lie in abutting relation with 10 said rear wall, and means for circulating a cooling medium through said tubes.

6. In a furnace having front and rear walls, the combination of an inclined grate stoker, extending rearwardly from said front wall, said 15 stoker comprising alternately disposed retorts and tuyère rows, a series of dump plates provided at the rear of said stoker, and a series of fluid conducting tubes extending longitudinally of said stoker and overlying said retorts and 20 tuyère rows, some of said tubes extending rearwardly and overlying said dump plates.

7. In a furnace, having front and rear walls, the combination of an inclined grate stoker extending downwardly and rearwardly from said 25 front wall, said stoker comprising alternately disposed retorts and tuyère rows, one or more tubes mounted in cooling relation with each of said tuyère rows, an ash pocket disposed between said stoker and rear wall, said tubes being bent down- 30 wardly so as to form a portion of the front wall of said ash pocket, a header connected to the lower ends of said tubes, a fluid conducting tube extending longitudinally of each of said retorts and across the top of said ash pocket, said last 35 mentioned tubes being bent downwardly so as to form a portion of said rear wall, and a header connected to each of said last mentioned tubes.

8. In a furnace having front and rear walls, the combination of an inclined grate stoker, extending downwardly and rearwardly from said 40 front wall, said stoker comprising alternately disposed retorts and tuyère rows, an ash pocket disposed between said stoker and rear wall, a series of spaced fluid conducting tubes mounted 45 in cooling relation with said rear wall, a header connecting one end of each of said tubes, one or more fluid conducting tubes mounted in cooling relation with each of said tuyère rows, said tubes extending downwardly and forming a portion of 50 the front wall of said ash pocket, a tube extending longitudinally of each of said retorts, said last mentioned tubes extending rearwardly across the top of said ash pocket and terminating in said header first named at points located between 55 certain of said first mentioned tubes, and means 60 for circulating a cooling medium through all of said tubes.

9. In a furnace having front and rear walls, the combination of an inclined grate stoker, extending downwardly and rearwardly from said front 65 wall, said stoker comprising alternately disposed retorts and tuyère rows, an ash pocket disposed between said stoker and rear wall, a series of spaced fluid conducting tubes mounted in cooling 70 relation with said rear wall, a header con-

necting one end of each of said tubes, one or more fluid conducting tubes mounted in cooling relation with each of said tuyère rows, said tubes extending downwardly and forming a portion of the front wall of said ash pocket, a tube extending longitudinally of each of said retorts, said last 10 mentioned tubes extending rearwardly across the top of said ash pocket, and being bent downwardly so as to lie in abutting relation with said rear wall and between certain of said first mentioned 15 tubes, said last mentioned tubes terminating in said header first named, and means for circulating a cooling medium through all of said tubes.

10. In a furnace having front and rear walls, the combination of an inclined grate stoker extending downwardly and rearwardly from said 20 front wall, said stoker comprising alternately disposed retorts and tuyère rows, a series of fuel feeding elements mounted in the bottom of each of said retorts, a dead plate provided at the lower 25 end of each of said retorts and extending rearwardly from said fuel feeding elements, an ash pocket disposed between said stoker and rear wall, a fluid conducting tube mounted longitudinally of each of said retorts and substantially midway between adjacent tuyère rows, said tubes being disposed in spaced relation with respect to said fuel feeding elements and dead plates, and means for 30 circulating a fluid cooling medium through said tubes.

11. In a furnace having front and rear walls, the combination of an inclined grate stoker extending rearwardly from said front wall, said stoker comprising alternately disposed retorts and tuyère rows, fuel feeding elements provided in 35 the bottoms of said retorts, a dead plate provided at the lower end of each retort and extending rearwardly of said fuel feeding elements, an ash pocket disposed between said stoker and rear wall, one or more fluid conducting tubes mounted 40 in cooling relation with each of said tuyère rows, the lower portions of said tubes being bent downwardly so as to form a portion of the front wall of said ash pocket, a fluid conducting tube extending longitudinally of each of said retorts and 45 lying in spaced relation with said fuel feeding elements and dead plates, said last mentioned tubes extending rearwardly across the top of said ash pocket and being bent downwardly so as to form a portion of said rear wall, and means for 50 circulating cooling medium through said tubes.

12. In a furnace having front and rear walls, the combination of an inclined grate stoker extending rearwardly from said front wall, said stoker comprising alternately disposed retorts and tuyère rows, fuel feeding elements provided in the bottom of each of said retorts, a dead plate provided at the lower end of each of said retorts and extending rearwardly of said fuel feeding elements, said dead plates being rounded at the 60 rearwardly disposed ends thereof forming an overfeed section, a fluid conducting tube extending longitudinally of each of said retorts and substantially midway between adjacent tuyère rows, said tubes being disposed in spaced relation with 65 said fuel feeding elements, and the lower portions thereof lying in cooling relation with said dead plates, said tubes extending rearwardly across said ash pocket, and means for circulating a cooling medium through said tubes.

13. In a furnace having front and rear walls, the combination of a stoker, said stoker extending rearwardly from said front wall and comprising alternately disposed retorts and tuyère rows, fuel feeding elements provided in the bottom of each 70

of said retorts, a fluid conducting tube extending longitudinally of each of said retorts, and means provided at the lower side of each of said tubes for deflecting the fuel fed by said fuel feeding elements toward said tuyère rows.

- 5 14. In a furnace having front and rear walls, the combination of a stoker, said stoker extending rearwardly from said front wall and comprising alternately disposed retorts and tuyère rows,
10 fuel feeding elements provided in the bottom of each of said retorts, a dead plate mounted in each retort at the bottom thereof and extending rear-

wardly of said fuel feeding elements, one or more fluid conducting tubes extending longitudinally of each of said tuyère rows, a fluid conducting tube extending longitudinally of each of said retorts and in substantially parallel relation with said first mentioned tubes, and means provided at the lower side of each of said last mentioned tubes and extending over the portion thereof disposed above said fuel feeding elements for deflecting the fuel fed by said elements toward 10 their tuyère rows.

WILLIAM V. SAUTER.
